tems Incorporated, Chicago, Ill., a corporation
of Illinois**

Application February 14, 1946, Serial No. 126,558

Term of patent 14 years

(Cl. D64—11)

To all whom it may concern:

Be it known that we, Hunter E. Hooe and Thomas O. Mehan, citizens of the United States, residing at Chicago and Park Ridge, respectively, in the county of Cook and State of Illinois, have jointly invented a new, original, and ornamental Design for a Combined Card Punching Machine and Stand, of which the following is a specification, reference being had to the accompanying drawing, forming a part thereof.

The figure is a perspective view of a combined card punching machine and stand showing our new design, the opposite side not shown, and the back being plain.

We claim:

The ornamental design for a combined card punching machine and stand, as shown and described.
